Primary Examiner — Ralf Seifert

(57) **CLAIM**

I claim the ornamental design for a carabiner keyring, as shown.

DESCRIPTION

FIG. 1 is a front view of the carabiner keyring showing my new design;

FIG. 2 is a reverse view thereof; and,
FIG. 3 is a perspective view thereof.

The claimed carabiner keyring is used to securely retain keys and other attached objects while additionally having the actions of a carabiner.

1 Claim, 3 Drawing Sheets

FIG.1

FIG. 2

FIG. 3
